The ornamental design for a cap lamp, as shown and described.

DESCRIPTION

FIG. 1 is a front, right, and top perspective view of a cap lamp, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a cross-sectional view of the cap lamp of FIG. 1, taken along section line 8-8 as depicted in FIG. 6; and, FIG. 9 is a partial enlarged view of an area labeled 9 in FIG. 1 comprising a Bluetooth receiver.

The broken lines shown in the drawings are included for the purpose of illustrating portions of the cap lamp that form no part of the claimed design. The additional dash-dot-dash lines surrounding the detail views in FIGS. 1 and 9 are for annotative purposes only and form no part thereof.
